(21) Appl. No.: **29/170,590**

CLAIM

(22) Filed: **Nov. 12, 2002**

I claim the ornamental design for a poptop aluminum can lotion dispenser, as shown and described.

(51) LOC (7) Cl. **09-01**

DESCRIPTION

(52) U.S. Cl. **D9/300**

FIG. 1 is a side elevation view of a poptop aluminum can lotion dispenser, showing my new design; the opposite side elevational view being a mirror image of that shown;
FIG. 2 is a front elevation view thereof;
FIG. 3 is a back elevation view thereof;
FIG. 4 is a top plan view thereof; and,
FIG. 5 is a bottom plan view thereof.

(58) Field of Search D9/300, 500, 502, D9/503, 504, 505, 557, 545, 570; D20/4, 5; 222/146.3, 146.1; 215/382, 384; 220/905, 906; 206/210, 409; D6/515, 518

The broken line showing of the words "Artwork Goes Here" is for illustrative purposes only and forms no part of the claimed design.
